UNITED STATES PATENT OFFICE.

JAMES MONTGOMERY, OF CHICAGO, ILLINOIS.

IRON FOLDING BEDSTEAD.

SPECIFICATION forming part of Letters Patent No. 637,146, dated November 14, 1899.

Application filed February 18, 1899. Serial No. 705,975. (No model.)

To all whom it may concern:

Be it known that I, JAMES MONTGOMERY, a citizen of the United States, residing at Chicago, in the county of Cook and State of Illinois, have invented certain new and useful Improvements in Iron Folding Bedsteads, which are fully set forth in the following specification, reference being had to the accompanying drawings, forming a part hereof, and in which—

Figure 1 shows my said iron folding bedstead in side elevation in open position. Fig. 2 shows the same when folded. Fig. 3 shows the mechanism which actuates the canopy. Fig. 4 shows an enlarged view of the jointed post of the foot-end legs, together with fragments of the parts which actuate said legs. Fig. 5 shows the legs of Fig. 4 turned quarter-way around, with fragments of the mechanism which actuates said legs. Fig. 6 shows the head end of the bedstead, with the canopy in its upper position shown in broken lines. Fig. 7 shows in plan one side rail and a fragment of a fabric or wire mattress. Fig. 8 shows a side view of the joint of the side rail. Fig. 9 shows a plan view of the joint of the side rail.

Like letters of reference denote like parts of the figures.

The object of my invention is to provide an iron folding bedstead provided with a woven-wire mattress. To attain said desirable end, I construct my new bedstead in substantially the following way, namely:

The tubular posts *a* have the usual T-shaped pipe-fixtures *a'*, into which are screwed pipe-pieces *d*, into which slide pipes or rods *e*, secured in elbows *f*, provided with legs *f'*, which are connected by a cross-rod *j'*. Inside of said parts *d e f* is the side rail *b*, pivoted at *f'* to the elbow *f* and hinge-jointed at *l* and *c* between the parts *l* and *f*. The foot-end posts have their T-shaped fixtures *r*, to which the rails *b* are attached. Said fixtures have each a hole *g*, into which slip the upper ends of the legs *h*, which are provided with slots *h'*, through which passes a pin *i* in the lower end of said hole, the inner side of said fixtures *r* being cut away, as seen in Fig. 4, to allow said legs to turn on the pin *i* to the position shown in Fig. 2. To the transverse connecting-rods *j j'* is attached a bar or rod *k*, and

to the inner rod *e* or any of the moving parts *f f' f'* is attached a cord *n*, passing under the pin *l*, thence up through the post *a* and out over a pulley *o* near the top of said post, and to a canopy *m*, hinged at *m'* to either a pin in each post or a rod *m'* connecting the posts *a*.

Cross-bars *t*, connected to the side bars *b*, hold the woven-wire fabric *w*, and a rod *p* near the joint *c*, held by the side rails either over or in the fabric *w*, holds the fabric down and from stretching directly from the bars *t* to *t*, so as to enable a single person to extend the bedstead, otherwise impossible when the web reached directly from bar to bar *t*, as such tension would raise the head end of the bedstead. In Figs. 8 and 9, *c'* shows another and preferred form of hinge.

The web *w* must have a certain amount of tension to make it useful, which is attained by my hinge-jointed and pivoted side rails fulcrumed so as to form a toggle-joint of great power.

The bedstead is folded by raising the foot end, which depresses and opens the joints at the hinges *c* and brings the upper end of the slot *h'* on the pin *i*. Said action also shortens the space between the parts *a* and *f'*, which draws on the rod *k* and brings the legs *h* inward parallel to the bars *b*. Said inward motion of the legs *f'* slackens the cord *n*, and thus allows the canopy to move from its elevated position (shown in broken lines) to the position shown in full lines in Figs. 2 and 3. Said canopy is here shown as a wire or rod to hold a curtain or curtains; but it may be of any other suitable material and form.

In unfolding the bedstead the rod *p* holds the fabric near to or below the hinge at *c*, and thus pulls in such a manner through the agency of said rod *p* as will stretch the fabric *w* without tilting up the head end of the bedstead and give said fabric its necessary tension by the work of a single person, an act which would fail and cause the head end to rise in the air if said rod *p* or a similar device were omitted.

By unfolding the bedstead the above-described actions of the several parts will be reversed and assume the position shown in Fig. 1.

I have shown elastic woven-wire fabric connected to my side rails, which works in con-

nection with my intermediately-hinged side rails and makes a very simple and desirable structure; but it is not essential to have said web, as the said web may be replaced by any 5 other suitable spring-bottom without interfering with the operation of the canopy or the mechanism that operates it or with the folding of the bedstead.

What I claim is—

- 10 1. The combination with head and foot ends and intermediately-hinged side rails pivoted to said ends, of reciprocable supports pivoted to said rails, intermediate said ends, and means to hold said intermediate supports 15 erect, substantially as specified.
2. The combination with the head and foot ends and intermediately-hinged side rails con-

necting said ends and reciprocable supports pivoted to said rails, intermediate said ends, of a hinge-operated canopy and cord connecting said canopy and said reciprocable supports, substantially as specified. 20

3. The combination with the head and foot ends and intermediately-hinged side rails connecting said ends, an intermediate reciprocable support for said rails, of a woven web held at the ends of said rails, and a bar connecting said rails and holding said web to said rails near the hinges of said rails, substantially as specified. 25

JAMES MONTGOMERY.
